(57) **CLAIM**

The ornamental design for a bun with insert, as shown and described.

DESCRIPTION

FIG. 1 is a front, top, and left side perspective view of a bun with insert;

FIG. 2 is an exploded front, top, and left side perspective view of the bun with insert of FIG. 1;

FIG. 3 is a top plan view of the bun with insert of FIG. 1; FIG. 4 is a bottom plan view of the bun with insert of FIG. 1;

FIG. 5 is a front elevation view of the bun with insert of FIG. 1, with the rear elevation view being a mirrored image thereof;

FIG. 6 is a cross-sectional view of the bun with insert taken along line A-A of FIG. 3;

FIG. 7 is an exploded front elevation view of the bun with insert of FIG. 2, with the exploded rear elevation view being a mirrored image thereof;

FIG. 8 is an exploded cross-sectional view of the bun with insert taken along line A-A of FIG. 3;

FIG. 9 is a right side elevation view of the bun with insert of FIG. 1, with the left side elevation view being a mirrored image thereof;

FIG. 10 is a cross-sectional view of the bun with insert taken along line B-B of FIG. 3;

FIG. 11 is an exploded right side elevation view of the bun with insert of FIG. 2, with the exploded left side elevation view being a mirrored image thereof; and,

FIG. 12 is an exploded cross-sectional view of the bun with insert taken along line B-B of FIG. 3.

The broken lines represent structure or features that form no part of the claimed design.

1 Claim, 4 Drawing Sheets
